(57) **CLAIM**

The ornamental design for a multifunctional plier, as shown and described.

DESCRIPTION

FIG. 1 is a front, right side, top perspective view of a multifunctional plier showing my new design;

FIG. 2 is a rear, left side, top perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front, right side, top perspective view thereof showing some of the component parts of the multifunctional plier respectively disposed at their open positions; and, FIG. 10 is a front, right side, top perspective view thereof showing the multifunctional plier disposed at a completely closed or collapsed state.

The broken lines depict portions of the multifunctional plier that form no part of the claimed design.

1 Claim, 10 Drawing Sheets
